UNITED STATES PATENT OFFICE

126,554

DESIGN FOR A ROASTER

John Carroll Fletcher, Dunbar, W. Va.

Application September 17, 1940, Serial No. 95,148

Term of patent 14 years

To all whom it may concern:

Be it known that I, John Carroll Fletcher, a citizen of the United States and a resident of Dunbar, in the county of Kanawha and State of West Virginia, have invented a new, original, and ornamental Design for a Roaster, of which the following is a specification, reference being had to the accompanying drawing, forming part thereof, in which:

Figure 1 is a perspective view of a roaster, showing my new design.

Figure 2 is a perspective view of the body of the roaster, the cover being omitted.

Figure 3 is an inverted perspective view of the body of the roaster, the cover again being omitted.

I claim:

The ornamental design for a roaster, as shown.

J. CARROLL FLETCHER.
